JAMES McALEAR, OF ST. PAUL, MINNESOTA.

VALVE FOR SPRINKLER SYSTEMS.

967,956.

Specification of Letters Patent. Patented Aug. 23, 1910.

Application filed November 18, 1905. Serial No. 287,992.

To all whom it may concern:

Be it known that I, JAMES McALEAR, of St. Paul, Ramsey county, Minnesota, have invented certain new and useful Improvements in Valves for Sprinkler Systems, of which the following is a specification.

This invention relates to dry pipe sprinkler valves, and particularly to that type wherein both the inlet and discharge ports 10 are provided with valves, the one leading to the system being normally held in its closed position by the pressure in the system.

The object of my invention is to provide an improved locking means for the inlet 15 valve, which will hold it securely closed until the pressure in the system is relieved.

A further object is to provide a lever mechanism for controlling the movement of the inlet valve which will not require any 20 delicate or fine adjustments when the valve is being set or put in working order.

The invention consists generally in providing a locking mechanism between the 25 water inlet valve and the one leading to the sprinkler system.

In the accompanying drawing forming part of this specification, the figure represents a vertical sectional view of a dry pipe 30 sprinkler system valve embodying my invention.

In the drawing, 2 represents a casing divided interiorly by a transverse wall 3 into chambers or compartments 4 and 5, the former having a port 6 communicating with 35 the water supply, and the latter a port 7 leading to the system. The wall 3 is provided with a port 8 above and in line with the port 6, and adapted to be closed by a valve 9 carried by a lever 10 pivoted at 11 40 on one side of the port 8. An auxiliary port 12 is provided in the wall 3 and normally closed by an auxiliary valve 13 carried by the lever 14, which is pivoted at 15 on said wall. The valves 9 and 13 being arranged 45 to open into the system will be locked and securely held in that position when pressure is on the system. The lever 10 has a recess 16 in its free end to receive a spring 17 on the casing 2 for the purpose of holding 50 the valve in its open or unlocked position.

A valve 18 is arranged to close the port 6, and a lever 19 pivoted at 20 on one side of said port has a bolt 21 provided with a ball and socket connection 22 with the valve 18. 55 The bolt 21 is capable of adjustment to allow the valve to be properly seated. An arm 23

is pivoted at 24 on the wall 3, and is free to swing toward the left and allow the lever 19 to pass by when the valve 18 is opened. A tooth 25 limits the movement of the arm 23 toward the right, and consequently will cause the valve 18 to be held in its open position. A lever 25 is pivoted at 26 at one end of the lever 19, and has a lug 27 whereon links 28 are pivoted. These links have 65 longitudinal slots 29 and an antifriction roller 30 mounted therein, and adapted to bear on the free end of the lever 19 between it and the under side of the lug 27. A hub 31 is mounted on a shaft 32 and free to oscillate thereon, and has a recess 33 to receive the upper end of the lever 25, said recess being of sufficient length to allow a limited oscillation of said hub. An arm 34 is provided on said hub having pivoted links 35 provided with slots 36 and an antifriction roller 37. A hub 38 is loosely mounted on a shaft 39 and carries a yoke 40, between which and said hub the end of the arm 34 is inserted, the antifriction roller 37 contacting with 80 said hub and with the end of said arm.

A recess 41 is provided in the shaft 39 to receive a lug 42 on the hub 38 and allow a limited oscillation of said hub. An arm 43 is mounted on said hub and provided with a weight 44. A pin 45 has a bearing surface 46 at its lower end on said hub, and is pivotally connected at its upper end with the auxiliary valve 13, so that when pressure is relieved on said valve the weight 44 will 90 drop and oscillate the hub 38, lift the auxiliary valve from its seat, and operate the mechanism connecting said auxiliary valve with the main valve to release it also and allow the water to flow into the casing, and 95 from thence to the system. An arm 46' is pivoted at 47 on the casing 2 in the path of the weight 44, and carries a lug 47' provided with a block 48 of insulating material arranged to slip between the spring plates 49 and separate them and break an electric circuit (not shown) to be connected with the point 50. The lug 47' contacts with the wall of the casing and limits downward movement of the arm 46'. As soon as the weight 44 falls and oscillates the lever 46', the insulating block 48 will be withdrawn from between the plates 49 and allow them to come together and close the circuit and cause the alarm to be sounded.

In operation: The inlet and discharge port valves are closed and pressure admitted

to the system. The lever mechanism connecting the auxiliary and inlet valves is then adjusted, so that when the pressure is relieved in the system the auxiliary valve will 5 be automatically opened and the inlet valve unlocked. The compound lever mechanism is positive and reliable in its action, and will require no delicate adjustment in setting the valve. The mechanism is at one 10 side of the inlet and discharge ports, and will not therefore offer any obstruction to the passage of water through them.

I claim as my invention:

15. 1. A valve for a sprinkler system comprising a casing having main and auxiliary discharge ports and an intake port for connection respectively with the sprinkler system and the water intake pipe, valves for said ports, those for the ports leading to the 20 sprinkler system being normally closed by the pressure therein, and means connecting said sprinkler system auxiliary valve with said water inlet valve whereby the latter will be locked in its closed position until 25 the pressure is reduced in the system, and said locking means being out of line with said intake and auxiliary discharge ports when the valves are closed and when open, substantially as described.
30. 2. A valve for a sprinkler system comprising a casing having water inlet and main and auxiliary discharge ports for connection respectively with the water intake pipe and the sprinkler system, valves for said ports, said sprinkler system valves being located in the same chamber of the casing and normally closed by the pressure therein, and means connecting said auxiliary valve and said water inlet valve whereby the latter 35 will be locked in its closed position until said auxiliary valve is released by the reduction of pressure in the system, substantially as described.
40. 3. A valve for a sprinkler system comprising a casing having water inlet and main and auxiliary discharge ports for connection respectively with the water intake pipe and the sprinkler system, valves for said ports, said sprinkler system valves being located in the same chamber of the casing and normally closed by the pressure therein, means connecting said auxiliary valve and said water intake valve and whereby the latter 45 will be locked in its closed position until said auxiliary valve is released by the reduction of pressure in the system, and said locking means offering no obstruction to the flow of water between said inlet and main discharge ports, substantially as described.
50. 4. A valve for a sprinkler system comprising a casing having water inlet and main and auxiliary discharge ports, valves for said ports, those for the ports leading to the 55 sprinkler system being located in the same 60

chamber of the casing and arranged to be normally closed by the pressure therein, and a lever mechanism connecting said auxiliary valve and said water inlet valve and whereby the latter will be locked in its closed position until said auxiliary valve is released by the reduction of pressure in the system, substantially as described. 70

5. A valve for a sprinkler system comprising a casing having water inlet and main and auxiliary discharge ports for connection respectively with the water inlet pipe and the sprinkler system, there being a substantially straight waterway between said water inlet and main discharge ports, valves for 80 said ports, those for the ports leading to the sprinkler system being located in the same chamber of the casing and normally closed by the pressure therein, and a lever mechanism connecting said auxiliary valve and said water inlet valve whereby the latter will be locked in its closed position until the pressure is relieved on said auxiliary valve, substantially as described. 85

6. A valve for a sprinkler system comprising a casing having ports for connection respectively with the water supply and the sprinkler system and having a wall dividing said casing into compartments or chambers, said wall having main discharge and auxiliary ports, valves for said main discharge and auxiliary ports located in the same chamber of the casing and adapted to be held in a closed position by the pressure in the system, a water inlet valve, and means connecting said auxiliary valve and said water inlet valve and normally locking the latter in its closed position until the pressure is relieved in the system upon said auxiliary valve, substantially as described. 90

7. A valve for a sprinkler system comprising a casing having ports for connection respectively with the water supply and the sprinkler system, a wall dividing said casing into compartments and having a discharge port in line with said water intake port and an auxiliary port at one side thereof, main discharge and auxiliary valves located in the same chamber of the casing and arranged to close their ports respectively 100 and be held in such position by the pressure in the system, a water inlet valve and means connecting said auxiliary valve and said water inlet valve and arranged to hold the latter in its closed position until the pressure is relieved in the system and on said auxiliary valve, substantially as described. 115

8. A valve for a sprinkler system comprising a casing having ports for connection respectively with the water supply and the sprinkler system, and a wall dividing said casing into compartments or chambers and having main discharge and auxiliary ports forming communicating passages through 120 said wall, main discharge and auxiliary 125 ports

valves arranged to close said ports and be held in their closed position by the pressure in the system, a water inlet valve, an oscillating hub connected with said auxiliary valve, and a lever mechanism arranged between said hub and said water inlet valve and adapted to hold said water inlet valve in its closed position until the pressure on said auxiliary valve is released, substantially as described.

9. A valve for a sprinkler system comprising a casing having ports for connection respectively with the water supply and the sprinkler system, main and auxiliary discharge valves located in the same chamber and arranged to control the flow of water to the system and normally held in their closed position by the pressure in the system, a water inlet valve, a pivoted locking lever therefor, a second lever having an antifriction bearing on said first named lever, and means connecting said second lever with said auxiliary valve and arranged to be actuated by the reduction of the pressure in the system to disengage said locking levers and release said water inlet valve, substantially as described.

10. A valve for a dry pipe sprinkler system having water inlet and main and auxiliary discharge ports and valves therefor, the valves for said discharge ports being normally held in their closed position by the pressure in the system, an oscillating hub provided with a weight, a pin connecting said auxiliary valve and said hub and preventing the oscillation of said hub until the pressure on said auxiliary valve is released, a second hub, and means for holding it against oscillation until released by said first named hub, and locking levers arranged to hold said water inlet valve in its closed position and actuated to release the same by the movement of said second named hub, substantially as described.

45 11. A valve for a sprinkler system com-

prising a casing having ports for connection respectively with the sprinkler system and the water intake pipe, and having a wall dividing said casing into compartments or chambers, said wall having main discharge and auxiliary ports, valves for said main discharge and auxiliary ports located in the same chamber of the casing and adapted to be held in a closed position by the pressure in the system, a valve for the inlet port, means connecting said auxiliary valve and said water inlet valve and normally locking the latter in its closed position until the pressure is relieved in the system upon said auxiliary valve and means on said wall for holding the water inlet valve in its open position, substantially as described.

12. A valve for a sprinkler system comprising a casing having water inlet and main and auxiliary discharge ports for connection respectively with the water supply and the sprinkler system, main and auxiliary discharge valves arranged to close said ports and be held in their closed position by the pressure in the system, a water inlet valve, an oscillating hub connected with said auxiliary valve, a lever mechanism arranged between said hub and said water inlet valve adapted to hold said water inlet valve in its closed position until the pressure on said auxiliary valve is released, an arm mounted on said oscillating hub provided with a weight, said weight being adapted to open said auxiliary valve when the pressure thereon is decreased and to swing and complete an electric circuit thus sounding an alarm, when the said auxiliary valve is opened, substantially as described.

In witness whereof, I have hereunto set my hand.

JAMES McALEAR.
